UNITED STATES PATENT OFFICE.

MORTIMER NORDEN, OF NEW YORK, N. Y., ASSIGNOR TO THE NORDEN-BITTNER ELECTRIC COMPANY, OF NEW YORK, N. Y., A CORPORATION OF NEW YORK.

SIGNAL FOR TRAVELING CABLES.

SPECIFICATION forming part of Letters Patent No. 712,201, dated October 28, 1902.

Application filed November 23, 1901. Serial No. 83,384. (No model.)

To all whom it may concern:

Be it known that I, MORTIMER NORDEN, a citizen of the United States, residing in the borough of Manhattan, city, county, and State 5 of New York, have invented new and useful Improvements in Signals for Traveling Cables, of which the following is a specification.

My invention is designed as an improvement upon the device shown and described 10 in Letters Patent granted to me September 22, 1896, No. 568,205. The device of said patent had special reference to the cables of cable-railways, while the device of my present invention is applicable to any traveling cable, 15 whether the same be used as the cable of a cable-railway or the cable of an elevator, hoisting device, or any power appliance whatsoever.

The object of the present invention, as of 20 the former patent, is to provide a device electrically actuated and which shall instantly detect one or more broken strands of the cable and give notice thereof, so that the cable may be at once stopped for the purpose of 25 making repairs and before there has been time for any damage to be done by the broken strand, it being a recognized fact that it is substantially impossible for any one to so 30 watch a moving cable as to detect a broken strand unless the same is exceedingly manifest.

In my present invention I employ grooved 35 guide-rollers for maintaining the cable in position and electrical devices and circuits similar to those shown and described in my aforesaid patent, and in combination therewith I employ a conductor closely surrounding the cable, but not in contact therewith, and an insulating-support for the same. This device 40 I prefer to comprise slabs of insulating material between which the cable is adapted to pass and upon said slabs one or more circuit-closing blades extending transversely of the said slabs and having an aperture through 45 which the cable passes, there being suitable binding-posts and a spring-blade bearing upon the cable and to which the wires of the circuit devices are connected.

In the operation of the device a broken 50 strand of the moving cable comes in contact

with the said blade devices and completes a main circuit, drawing over the armature of the relay and closing the local circuit and causing the bell therein to ring and give the alarm, so that the cable can be stopped and 55 the damage repaired.

In the drawings, Figure 1 represents a dia- 60 grammatic view including a vertical section of parts illustrative of my invention. Fig. 2 is a plan of the circuit-closing blades and their insulating-supports. Fig. 3 is a side elevation of the same, and Figs. 4 and 5 are plans of modified forms of circuit-closing 65 blades and their insulating-supports.

The cable is represented at *a*, and at *b b'* 70 are represented pairs of grooved guide-wheels between which the cable passes.

c c' represent slabs of insulating material connected to end supports *c²*, and between these slabs the cable passes through semicircular notches in the opposite adjacent edges 70 of the said slabs. The said end supports *c²* may have other supports of any desired character.

In Figs. 1 and 2 I have shown circuit-clos- 75 ing blades *d d'* on the slabs *c c'*, with opposite circular end notches and prongs adjacent to said notches, the prongs of one blade overlapping those of the adjacent blade and the blades secured to the slabs *c c'* by screws 80 or in any other manner, and the binding-posts 12 13 may be part of the means em- 85 ployed for securing the said blades to the said slabs. *e* represents a post secured to the under side of the slab *c*, of insulating mate- 90 rial, and this post is provided with a spring- 95 blade *e'*, bearing upon the cable.

The wire 2 of the main circuit connects with the post *e*, and the wire 3 of the main circuit connects with the binding-posts 12 13. 90 In the main circuit there is a battery 4 and a relay-magnet 5, and in the local circuit connected to said relay I have included the armature 6, wires 7 and 8, a battery 9, and switch 10, and the call-bell 11.

In the operation of the device the cable runs through the aperture formed between the adjacent slabs *c c'* and between the notched ends of the circuit-closing blades *d d'*, the aperture in the slabs being of less di- 100

ameter than that in and between the ends of the blades, so that the slight swinging of the cable would contact with the insulating material and not with the metal. Thus an accidental completion of the circuit is avoided.

In the case of a broken strand the ends of course protrude from the body of the cable, and with the movement of the cable through the aforesaid parts said strands come in contact with one of the blades d d' , thus completing the circuit through the battery 4, wire 3, one of the binding-posts 12 or 13, the cable, spring-blade e' , wire 2, and relay-magnet 5, moving the armature 6 and closing the local circuit and ringing the bell 11 to give the alarm to the attendant in charge, so that the machinery moving the cable can be stopped and the broken strand of the cable repaired.

In Fig. 4 I have shown a circuit-closing blade d^2 with an opening larger than the opening through and between the slabs of insulating material c c' , and through which opening the cable passes, as it is possible to employ a single plate and a single binding-screw 14 in completing the circuit when the broken strand comes in contact with said plate. I have also shown in Fig. 5 a single plate d^3 , similar to the plate d^2 in Fig. 4, but provided with radial incisions forming tongues, and also a single binding-post 14. The tongues of the plate d^3 have a yielding function upon contact therewith of the broken strands of the cable similar to the function of the plates d d' in the other figures, it being advantageous that said plates shall yield slightly to obviate the liability of injury to the parts.

I claim as my invention—

1. The combination with the traveling cable and supports for maintaining it in position, of slabs of insulating material between which the cable passes, a metallic conducting means extending across the path of the said cable and secured to the slabs and having an aperture through which the cable passes, electrical connections to said conducting means and a device connected to a slab of insulating material and bearing upon the cable, and electric-circuit connections therefrom, and an alarm brought into action by a broken strand or projection from the cable, substantially as set forth.

2. The combination with the traveling ca-

ble and rollers for guiding the same, of adjacent slabs of insulating material having opposite edge notches forming a circular aperture through which the cable passes, devices connecting the said slabs of insulating material and supporting the same, a metallic conducting means extending transversely across the path of the cable and secured to said slabs and having an aperture of larger diameter than the aperture for the cable between the said slabs, a binding-post upon said metallic device, a post and spring-blade bearing upon the cable and secured to one of said slabs of insulating material, and electric-circuit connections from said posts, and an alarm brought into action by a broken strand or projection from the cable, substantially as specified.

3. The combination with the traveling cable and rollers for guiding the same, of adjacent slabs of insulating material having opposite edge notches forming a circular aperture through which the cable passes, devices connecting the said slabs of insulating material and supporting the same, a circuit-closing device extending across the path of the cable at right angles to the slabs and having an aperture of larger diameter than the aperture for the cable between the slabs and having prongs, a binding-post connected to said circuit-closing device, a post and spring-blade connected to one of the slabs of insulating material and bearing upon the traveling cable, electric-circuit connections from said posts and an alarm brought into action by a broken strand or projection from the cable, substantially as specified.

4. The combination with a cable and supports for the same, of a conductor in the form of a metal plate extending across the path of the cable and closely concentric with the surface of the cable but not in contact therewith, an insulating-support for the conductor, and electric-circuit connections to said cable and conductor, and an alarm brought into action by a broken strand or projection from the cable, substantially as set forth.

Signed by me this 31st day of October, 1901.

MORTIMER NORDEN.
